DISPOSABLE VIAL FOR BLOOD CELL COUNTING

Patrick V. Ferro, Miami Lakes, and Laureston C. Brown, Miami Springs, Fla., assignors to Coulter Diagnostics, Inc., Hialeah, Fla.

Filed Apr. 23, 1970, Ser. No. 22,601

Term of patent 14 years

Int. Cl. D24—02

U.S. Cl. D16—1

FIG. 1 is a perspective view of a disposable vial for blood cell counting illustrating our new design;

FIG. 2 is a front elevational view of the same;

FIG. 3 is a top plan view of the same;

FIG. 4 is a bottom plan view of the same.

We claim:

The ornamental design for a disposable vial for blood cell counting, substantially as shown.
